Primary Examiner — R. Johnson

(57) **CLAIM**

The ornamental design for a guitar, as shown and described.

DESCRIPTION

1. Guitar
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Enlarged
- 1.12 : Enlarged
- 1.13 : Exploded

The parts shown by means of broken lines in the reproductions are not part of the claimed design; figs. 1.9 and 1.10 are enlarged views of the portion taken at lines 9 and 10 in fig. 1.1; figs. 1.11 and 1.12 are the enlarged views of the portion taken at lines 11 and 12 in fig. 1.2; the dash dot dash lines in the reproductions and the number "9", "10", "11" and "12" in figs. 1.1 and 1.2 are for the purpose of depicting the cut line of the enlarged views and form no part of the claimed.
